*Attorney, Agent, or Firm—Merchant, Gould, Smith,
Edell, Welter & Schmidt*

[57] **CLAIM**

The ornamental design for a panel, as shown and described.

DESCRIPTION

FIG. 1 is a top plan view of portion of the panel, showing my design and the open, repetitive form thereof; and FIG. 2 is a section, drawn to an enlarged scale, taken on line II—II of FIG. 1.

FIG.1

FIG.2
